G. POULOS

MILK DISPENSING APPARATUS

Filed Oct. 31, 1921

Inventor:
Gus Poulos
By Jas. L. Sweet
Atty

UNITED STATES PATENT OFFICE.

GUS POULOS, OF BOONE, IOWA.

MILK-DISPENSING APPARATUS.

Application filed October 31, 1921. Serial No. 511,734.

To all whom it may concern:

Be it known that I, Gus Poulos, a subject of the King of Greece, and resident of Boone, Boone County, Iowa, have invented 5 a new and useful Milk-Dispensing Apparatus, of which the following is a specification.

This invention relates to and is an improvement on the apparatus covered by Letters Patent of the United States Number 10 1,306,813, granted to me June 10, 1919.

An object of this invention is to provide improved means for mounting an agitator removably and replaceably in a receptacle.

Another object of this invention is to provide improved means for connecting an agitator to a spigot valve.

Another object of this invention is to provide an improved construction or shape 20 for an agitator blade.

My invention consists in the construction, arrangement and combination of elements hereinafter set forth, pointed out in my 25 claims and illustrated by the accompanying drawing, in which—

Figure 1 is a plan of the complete apparatus except that the cover is removed from the receptacles, dotted lines indicating subjacent elements. Figure 2 is a front elevation of the apparatus, a portion of the front wall being broken away to reveal the agitator. Figure 3 is a horizontal section on the indicated line 3—3 of Figure 2. Figure 35 4 is a detail view, on an enlarged scale, of a means employed for effecting a water-tight connection between the agitator shaft and the bottom of a receptacle.

In the construction of the device as shown 40 the numeral 10 designates generally a subdivided tank, which may be of any suitable size and construction, is adapted to be removably and replaceably mounted on a base 11 and is divided preferably into three or more compartments or receptacles designated 45 respectively by numerals 12, 13 and 14 and adapted for use in containing cream, ice water and milk. Each of the containers or receptacles is adapted to be drained by one or another of spigots or faucets 15, 16 and 50 17. A stub shaft 18 is mounted vertically in a hole arranged substantially centrally of the bottom of the receptacle 14 and is journaled in a gland or stuffing box 19 adapted to provide a milk-tight, non-leaking joint. 55 The stub shaft 18 is formed with a threaded

socket opening upwardly and an agitator shaft 20 is screwed at its lower end in and rises vertically from said socket, there being a winged locknut 21 screwed on said agitator shaft and adapted to engage the stub shaft 60 and securely connect said members. A plurality of agitating blades 22 are fixed to and extend substantially radially from opposite sides of the agitator shaft. Each of the blades 22 is curved longitudinally as to 65 width and also is arranged helically as to thickness. The blades 22 are so mounted that in the rotation of the shaft 20 in the direction of the arrow in Figure 1, said blades tend to effect a downward movement 70 of fluid such as milk or buttermilk encountered thereby, thus insuring that the liquid drawn for dispensing each time is properly agitated and possesses its proportionate share of the richness of the body of fluid 75 contained in the receptacle 14. A portion 23 of the stub shaft 18 is squared and a pinion 24 is mounted thereon and secured thereto by a nut 25 screwed on the lower extremity of said shaft, the pinion and nut 80 being beneath the bottom of the receptacle 14. A lever 26 is mounted on a vertical fulcrum 27 extending downward from the bottom of the receptacle 14 and said lever is formed with a segmental gear 28 on one end 85 adapted to mesh with the pinion 24. The gear 28 preferably has two to three times more teeth than the pinion 24. The spigot or faucet valve plug 29 extends downwardly 90 from the chamber 30 and an arm 31 is rigidly mounted at one end on and extends radially from the lower end portion of said plug. A slot 32 is formed in the apron 33 of the tank and the arm 31 extends through said slot and beneath the bottom of the receptacle 14 and is free to move through an arc therein. A link 34 pivotally connects the inner end portion of the arm 31 to the extremity of the lever 26.

As illustrated, the parts are shown in 100 closed positions. When it is desired to draw liquid from the receptacle 14 the handle 35 of the spigot or faucet 17 is turned substantially one-quarter of a revolution into a plane perpendicular with the front wall of 105 the tank, whereupon the arm 31 moves through an arc indicated by the arrow in Figure 3 and causes a corresponding movement of the toothed margin of the segmental gear 28 through operation of the link 34 110 and lever 26. The gear 28 rotates the pinion

24, stub shaft 18 and agitator 20 together. I claim as my invention—

1. In a dispensing apparatus having a tank, a spigot mounted externally of said tank and an agitating device mounted internally of said tank; the combination with said agitating device and spigot of a shaft vertically arranged and extending through the bottom of said tank, said agitating device screwed in and detachably carried by said shaft, a gland within said tank surrounding said shaft, a pinion on the lower end of said shaft, an arm on the lower end of the spigot, a lever fulcrumed on the bot-

tom of the tank and formed with a segmental gear meshing with said pinion, and a link pivotally connecting said arm and lever.

2. In a device of the class described, a stub shaft, an agitator shaft detachably screwed thereto, a winged lock nut on the agitator shaft engaging the stub shaft, and helical blades on the agitator shaft.

Signed at Boone, in the county of Boone and State of Iowa, this 26th day of September, 1921.

GUS POULOS.
